COMBINATION RECEPTACLE CAP AND
MULTIPLE LAMP HOLDER OR SIMI-
LAR ARTICLE

Philip G. Stone, Newark, N. J., assignor to Stone
Manufacturing Co., Elizabeth, N. J., a body cor-
porate of New Jersey

Application October 29, 1949, Serial No. 5,790

Term of patent 14 years

(Cl. D48—31)

To all whom it may concern:

Be it known that I, Philip G. Stone, a citizen of the United States, residing in the city of Newark, in the county of Essex and State of New Jersey, have invented a new, original, and ornamental Design for a Combination Receptacle Cap and Multiple Lamp Holder or Similar Article, of which the following is a specification, reference being had to the accompanying drawing forming a part hereof.

In the drawing:

Figure 1 is a top plan view of a combination receptacle cap and multiple lamp holder or similar article showing my new design;

Figure 2 is a front elevational view thereof;

Figure 3 is a rear view thereof;

Figure 4 is a side view thereof;

Figure 5 is a bottom view thereof;

Figure 6 is a perspective view showing the in-
side of the rear section; and

Figure 7 is a perspective view showing the in-
side of the front section.

I claim:

The ornamental design for a combination re-
ceptacle cap and multiple lamp holder or similar
article, as shown.

PHILIP G. STONE.
